[57] CLAIM

The ornamental design for a labelling apparatus, as
shown.

DESCRIPTION

FIG. 1 is a side elevational view taken from the right
side of the labelling apparatus embodying my new de-
sign;

FIG. 2 is an end elevational view taken from the left
hand end of FIG. 1;

FIG. 3 is an end elevational view taken from the right
hand end of FIG. 1;

FIG. 4 is a bottom plan view of the labelling apparatus
embodying my new design;

FIG. 5 is a side elevational view of the left hand side of
the labelling apparatus of my new design; and

FIG. 6 is a top plan view of the labelling apparatus
embodying my new design.
